Inventor:

James H. Boardman,

UNITED STATES PATENT OFFICE.

JAMES H. BOARDMAN, OF PORT HURON, MICHIGAN.

TIME CUT-OUT FOR ELECTRIC LAMPS.

SPECIFICATION forming part of Letters Patent No. 624,615, dated May 9, 1899.

Application filed July 14, 1898. Serial No. 685,914. (No model.)

To all whom it may concern:

Be it known that I, JAMES H. BOARDMAN, a citizen of the United States, residing at Port Huron, in the county of St. Clair and State of Michigan, have invented certain new and useful Improvements in Automatic Time Cut-Outs for Incandescent Electric Lights; and I do declare the following to be a full, clear, and exact description of the invention, such as will enable others skilled in the art to which it appertains to make and use the same.

My invention relates to cut-out switches for incandescent-electric-light-service circuits, and more particularly to that class of spring-actuated switches which are automatically operated at a certain predetermined time by a suitable clock-movement; and the object is to provide a simple, reliable, and effective device for this purpose.

The accompanying drawings show my invention in the best form now known to me; but many changes in the details might be made within the skill of a good mechanic without departing from the spirit of my invention as set forth in the claims at the end of this specification.

The same reference characters indicate the same parts of the device.

Figure 1 is a front elevation of my improved automatic time cut-out. Fig. 2 is a vertical section with the spring-actuated switch closed. Fig. 3 is an enlarged view with the switch open.

A denotes the non-conducting base, which may be of marble, porcelain, slate, hard rubber, vulcanized fiber, or the like, and it is securely fixed at a convenient point to the wall of the room or premises where the lights are used.

1 and 2 denote the lamp-circuit, the conductor 1 being electrically connected to the switch-post 3, and it terminates at the switch-post 4, while the conductor 2 is similarly connected to the switch-post 5 and terminates at the corresponding switch-post 6.

7 and 8 represent the main-line switch-posts, and 9 9' the main-line conductors.

10 and 12 denote the knife-blade switches, fulcrumed at their lower ends to the posts 7 and 8 and having their upper or free ends connected by the non-conducting bar 11, the switches when closed being seated in the slots

in the lamp-circuit terminal-posts 4 and 6, so that the lamp-circuit conductors 1 and 2 form a loop with the main-line conductors 9 55 and 9'.

13 14 denote conductor-plates fixed to the base A, and 15 and 16 represent the clock-circuit switch-posts, fixed on the plates 13 and 14, and 17 and 18 the knife-blade switch-levers, fulcrumed at their lower ends in said posts 15 and 16, respectively, and having their free ends connected by the non-conducting handle 19, the switch-levers when closed being seated in the slots in the lamp-circuit 65 posts 3 and 5.

32 and 33 denote leaf-springs having their lower ends fixed to the posts 7 and 8 and their free ends resting under the switch-blades 10 and 12, respectively.

20 denotes a conductor extending from the plate 13 to the binding-post 21, and 22 a conductor extending from said post 21 to the post 22, whence the current enters the magnet 23 and leaves it at the post 24, thence travels 75 through the leg 25 of the clock to the break-wheel 26, carried by the hour-hand shaft. 27 denotes a contact-spring resting on said break-wheel, and 28 a conductor extending from said contact-spring to the opposite leg 29 of the 80 clock, which is in electrical contact with the binding-post 30, from which a conductor 31 extends to the plate 5.

34 represents an incandescent-lamp socket in series with the lamp-circuit conductors 1 85 and 2 between the main-line switch 11 and the clock-switch 19.

35 represents the pivoted armature of the magnet 23, and its forward or free edge carries a keeper or pawl 36, which is adapted to 90 engage the beveled edge of the switch-bar 11 and retain the main-line switch in a closed position when the clock-circuit is open.

The operation of the device is as follows: Both switches are closed, as shown in Fig. 1. 95 The main-line current now passes through the main-line switch 11 to the lamp-circuit, which consists of the conductors 1 and 2, while the clock-circuit, which consists of the conductors 20 and 31, is open at the clock-wheel 26 and contact-spring 27. The break-wheel 26 is now set after the manner of an ordinary alarm-clock, so that its contact-bar 38 (which is electrically connected with the clock-leg 25)

will at the appointed time come in contact with the spring 27, thereby closing the clock-circuit through the magnet 23, energize the armature 35, which releases the bar 11 and 5 allows the springs 32 33 to force the free ends of the switch-blades 10 and 12 out of contact with the posts 4 and 6, thus opening the lamp-circuit, and consequently extinguishing all lights in the circuit. When it is desirable to 10 cut out the clock, the switch 19 is opened and the lamp-circuit 1 2 is energized as long as the main-line switch 11 is closed.

Having thus fully described my invention, what I claim, and desire to secure by Letters 15 Patent, is—

1. The combination with the clock-circuit, the break-wheel 26 and the contact-spring 27 and the electromagnet 23, of the armature 35, the main-line circuit and the main-line switch 20 11 having its free end traveling in the path of said armature, and the leaf-springs 32 33 op-

eratively connected to said switch, substantially as shown and described.

2. In an automatic time cut-out for incandescent-electric-lamp circuits, the main-line 25 circuit, the lamp-circuit, and the spring-actuated switch 11 arranged intermediate said circuits, in combination with the clock, the clock-switch 19, and the magnet 23 formed in the clock-circuit, and in series with said main-line circuit, and the pivoted armature 35 adapted to lock said spring-actuated main-line switch in a closed position, substantially 30 as and for the purpose set forth.

In testimony whereof I have hereunto set 35 my hand in presence of two subscribing witnesses.

JAS. H. BOARDMAN.
